UNITED STATES PATENT OFFICE.

JOSEPH M. MOLLOY, OF LEWISTON, IDAHO.

MOISTENER.

973,375.

Specification of Letters Patent. Patented Oct. 18, 1910.

Application filed August 6, 1909. Serial No. 511,564.

To all whom it may concern:

Be it known that I, JOSEPH M. MOLLOY, a citizen of the United States, residing at Lewiston, in the county of Nez Perce and 5 State of Idaho, have invented new and useful Improvements in Moisteners, of which the following is a specification.

This invention relates to moisteners designed particularly for office use in moistening the flaps of envelops, stamps and the like, and the object of the invention is to provide a simple, inexpensive and efficient device of this character which is always ready for use to facilitate the operation of 10 sealing envelops, moistening and applying stamps and performing other like work.

The invention consists of the combination and arrangement of parts hereinafter fully described and claimed, reference being had 20 to the accompanying drawing, in which;

Figure 1 is a central vertical sectional view through a moistener embodying my invention. Fig. 2 is a plan view of the washer. Fig. 3 is a side view of the stopper and the 25 upper portion of the wick.

Referring to the drawing, 1 designates a receptacle comprising a non-resilient bottom 2, a resilient or compressible body 3 and an internally threaded neck 4 at the upper 30 end of said body, which neck is internally screw-threaded and provided at its base with an annular flange or shoulder 5. The receptacle is preferably formed as a whole of rubber, and its body portion 3 is of sufficient resiliency to enable it to be compressed to a greater or less extent and adapt it to resume its normal shape after pressure has been removed. The body is also preferably made somewhat in the shape of an 35 hour glass, its upper portion being of diminished diameter with respect to its lower portion, providing an intermediate contracted portion 6, adapting the device to be more conveniently and securely held in the 40 hand and compressed as described. The receptacle is adapted to contain a body of water 7 for feed through a wick 8 which depends therein. The upper end of this wick, which is composed of felt or other absorbent 45 material and flat in cross-section, extends through a corresponding bore or passage in the stopper 9, which has an enlarged internally threaded lower end 10 inserted within 50 and engaging the threads of the neck 4, by

which the latter is closed against the discharge of the water. In order to seal the neck against possible leakage of water when the device is inverted in use, a gasket or sealing disk or washer 11 is cemented or otherwise secured to the bottom face of the 60 stopper and is clamped by the latter against the flange 5, as shown, thus preventing the upward passage of water through the stopper except through the wick 8.

The body portion of the stopper 9 is angular in form, being substantially flat, so that it will move over and in close proximity to the gummed surface of an envelop flap or a stamp without injury to said flap or stamp. The upper end of the wick 8 65 projects beyond the stopper to form a brush portion 12, which is adapted to be rubbed over the gummed surface to be moistened or to transfer a portion of the water contained therein thereto.

In priming the device for use, the receptacle is first filled to the desired height with water and is then sealed by applying the stopper. A proportion of the water will be taken up by the wick 8 and pass by capillary attraction to the end or brush surface 12, the amount being ordinarily sufficient for 70 use in moistening.

In the operation of the device, the receptacle is inverted and the brush surface 12 85 run over the gummed surface of the envelop or other surface to be moistened. If desired, however, the device may be left in normal upright position in applying stamps, and a row or strip of stamps, or individual 90 stamp, gummed by running the same over or pressing them against the brush surface 12. If, in the use of the device, a sufficient amount of water is not fed to the brush surface 12 through the body of the wick, this may be 95 compensated for and an additional amount supplied by compressing the resilient body 3 to bring the body of water into contact with the entire length of the wick or to forcibly expel a certain amount through the minute 100 space or crevice between the wick and the wall of the bore of the stopper 9 through which the wick passes.

The device will be found exceptionally useful in sealing envelops, as, after the 105 gummed surface of the flap of the envelop has been moistened and turned over, the bottom 2 of the receptacle may be wiped across

the outer face of the flap to compress its gummed surface against the body of the envelop and to secure an effective sealing action through a single motion of the hand of 5 the operator.

Having thus described the invention what I claim as new is:—

1. A moistener comprising a receptacle having a rigid bottom, a neck, and a flexible 10 expandible and contractible body, said body being provided with an annularly contracted central portion, a slotted plug secured within the neck, and a flat wick extending through the slot in the plug.

15 2. A moistener comprising a receptacle having a rigid base, a neck and a resilient body, said receptacle being adapted to contain a moistening fluid, a closure for the neck having a narrow rectangular slot extending therethrough, and a flat wick of absorbent material extending into the recep- 20

tacle and outward through the slot in said closure.

3. A moistener comprising a receptacle having a flat rigid base, an internally 25 threaded neck provided with a shoulder at the base thereof, and a resilient body inwardly offset or contracted at its center, a plug having a threaded portion engaging the threaded neck, and having a narrow rectangular slot extending therethrough, a gasket clamped between the plug and shoulder, and a flat wick depending into the receptacle and extending exteriorly through the slot in said plug. 30 35

In testimony whereof I affix my signature in presence of two witnesses.

JOSEPH M. MOLLOY.
